United States Patent Office.

CHARLES BURNHAM, OF PHILADELPHIA, PENNSYLVANIA.

Letters Patent No. 67,718, dated August 13, 1867.

IMPROVEMENT IN PAINT-CANS.

The Schedule referred to in these Letters Patent and making part of the same.

TO ALL WHOM IT MAY CONCERN:

Be it known that I, CHARLES BURNHAM, of the city and county of Philadelphia, State of Pennsylvania, have invented certain new and useful Improvements in Paint-Cans; and I do hereby declare the following description and accompanying drawings are sufficient to enable any person skilled in the art or science to which it most nearly appertains to make and use my said invention or improvements without further invention or experiment.

The nature of my invention and improvements consists in wiring or hemming the top edge of the can with a flat wire, so as to present a broad surface to the edge of the cover which shuts outside of the hem. Also, in a cover with the rim bent double, so as to shut against both the inside and outside of the top edge of the can; and in same clips or brackets to hold on the cover of the can; and in a sunken cover for the can, either corrugated or flat. In the accompanying drawing—

Figure 1 is an elevation of a paint-can with my improvements.

Figure 2 is a section of fig. 1 cut perpendicularly through the centre.

In these drawings, A is the cylinder of the can; B, the bottom; C, the cover, and D the bail arranged to swing in ears E fastened to the cylinder A.

The upper edge of the cylinder A is hemmed or turned over a flat wire, F, (the end of this wire is shown in section, fig. 2,) to make a broad surface for the outside edge of the cover C to shut against, and to bring the lower edge of the hem below the lower edge of the cover, as shown in the drawings, so that the clips or brackets G G can be hooked under the hem and bent over the edge of the cover to hold it on. The cover C may be made flat or corrugated, and the edge bent double, as shown in fig. 2, so as to form a groove and shut against both the inside and outside of the top edge of the can, as shown in fig. 2, to make a better and far more secure joint between the top edge of the can and cover than it would do if it shut against the outside of the can or hem only.

What I claim as my invention and improvement in paint-cans and other vessels, is—

Wiring or hemming the top edge of the can with a flat wire, so as to present a broad surface to the edge of the cover.

And in combination with the above-claimed improvement, I claim a cover with the rim bent double, forming a groove, so as to shut against both the inside and outside of the can at the top edge.

And in combination with the improvements above claimed, I claim the clips to hold on the cover.

I also claim a sunken cover, either corrugated or flat.

CHARLES BURNHAM.
